CLAIM

The ornamental design for a computer with graphical user interface, as shown and described.

DESCRIPTION

FIG. 1 is a front view of a computer with graphical user interface showing our new design;

FIG. 2 is a second embodiment thereof; and,

FIG. 3 is a third embodiment thereof.

The two outermost broken lines and the broken line oval depict a computer. The remaining broken lines depict a display screen and portions of the graphical user interface. All broken lines form no part of the claimed design.
